(57) **CLAIM**

The ornamental design for a wall panel, as shown and described.

DESCRIPTION

FIG. 1 is a front perspective view of a first embodiment of a wall panel according to our design;

FIG. 2 is a rear perspective view of the wall panel of FIG. 1;

FIG. 3 is a front view of the wall panel of FIG. 1;

FIG. 4 is a rear view of the wall panel of FIG. 1;

FIG. 5 is a top view of the wall panel of FIG. 1;

FIG. 6 is a bottom view of the wall panel of FIG. 1;

FIG. 7 is a left view of the wall panel of FIG. 1;

FIG. 8 is an enlarged view of the portion of the wall panel identified by window 8 in FIG. 7;

FIG. 9 is an enlarged view of the portion of the wall panel identified by window 9 in FIG. 7;

FIG. 10 is a right view of the wall panel of FIG. 1;

FIG. 11 is a front perspective view of a second embodiment of a wall panel according to our design;

FIG. 12 is a rear perspective view of the wall panel of FIG. 11;

FIG. 13 is a front view of the wall panel of FIG. 11;

FIG. 14 is a rear view of the wall panel of FIG. 11;

FIG. 15 is a top view of the wall panel of FIG. 11;

FIG. 16 is a bottom view of the wall panel of FIG. 11;

FIG. 17 is a left view of the wall panel of FIG. 11;

FIG. 18 is an enlarged view of the portion of the wall panel identified by window 18 in FIG. 17;

FIG. 19 is an enlarged view of the portion of the wall panel identified by window 19 in FIG. 17;

FIG. 20 is a right view of the wall panel of FIG. 11;

FIG. 21 is a front perspective view of a third embodiment of a wall panel according to our design;

FIG. 22 is a rear perspective view of the wall panel of FIG. 21;

FIG. 23 is a front view of the wall panel of FIG. 21;

FIG. 24 is a rear view of the wall panel of FIG. 21;

(Continued)

FIG. 25 is a top view of the wall panel of FIG. 21;
 FIG. 26 is a bottom view of the wall panel of FIG. 21;
 FIG. 27 is a left view of the wall panel of FIG. 21;
 FIG. 28 is an enlarged view of the portion of the wall panel identified by window 28 in FIG. 27;
 FIG. 29 is an enlarged view of the portion of the wall panel identified by window 29 in FIG. 27; and,
 FIG. 30 is a right view of the wall panel of FIG. 21.
 The drawings contain a symbolic break. The portion between the break lines forms no part of the claimed design. The dash-dash broken lines in the figures depict portions of the wall panel that form no part of the claimed design. The dash-dot-dash broken lines represent boundaries of the enlarged views and form no part of the claimed design.

1 Claim, 30 Drawing Sheets
